INTERNAL-COMBUSTION ENGINE

Lloyd E. Johnson, Fon du Lac Township, Taxewell County, and Carl R. Maxwell, Washington, Ill., assignors to Caterpillar Tractor Co., San Leandro, Calif., a corporation of California

Application August 25, 1943, Serial No. 499,892

4 Claims. (CL. 123—55)

Our invention relates to internal combustion engines, and more particularly to a radial internal combustion engine having solid fuel injection mechanisms.

Such type of engine presents the matter of providing mechanism for actuating and controlling the fuel injection mechanisms, and also for actuating valve tappet mechanisms associated with the cylinders on the engine. Our invention is primarily directed to such features, and has as its objects, among others, the provision of improved means for actuating and controlling the fuel injection mechanisms, and for actuating the cylinder valves; which is of relatively simple and economical construction; relatively easy to assemble; and which provides for accurate timing relationship of the fuel injection mechanisms. Other objects of our invention will become apparent from a perusal of the following description.

Referring to the drawings:

Fig. 1 is a sectional view along the crankshaft axis, of a form of radial internal combustion engine embodying the construction of our invention; parts being omitted from the view to disclose the construction more clearly and other parts being shown more or less schematically.

Fig. 2 is a fragmentary transverse section in a plane indicated by line 2—2 in Fig. 1.

Fig. 3 is a developed vertical sectional view, partly in elevation, of a preferred form of fuel injection pump mechanism embodied in the engine.

Fig. 4 is a horizontal sectional elevation taken in planes indicated by line 4—4 in Fig. 3.

Fig. 5 is a more or less schematic fragmentary section, illustrating the fuel passage arrangement in the engine.

Fig. 6 is a fragmentary section of a portion of the structure illustrated in Fig. 1; the view being enlarged compared to Fig. 1 to illustrate such structure more clearly.

Fig. 7 is a horizontal sectional elevation taken in a plane indicated by line 7—7 in Fig. 2.

Fig. 8 is a horizontal sectional elevation taken in planes indicated by line 8—8 in Fig. 2.

Fig. 9 is a fragmentary vertical section taken in a plane indicated by line 9—9 in Fig. 7.

Fig. 10 is a fragmentary vertical section taken in a plane indicated by line 10—10 in Fig. 7.

With particular reference to Figs. 1 and 6, the engine illustrated is a radial Diesel or compression ignition engine. However, it is to be understood that the features of our invention may be

employed in any other type of radial internal combustion engine, such as one of the spark ignition type having solid fuel injection mechanisms thereon. The engine comprises a crankcase 2 having a plurality of peripherally or circumferentially disposed cylinders 3; the cylinders being preferably of the air cooled type and having cooling fins 4. A precombustion chamber 6 is mounted in the head of each cylinder 4, and supports a fuel injection nozzle 7 of any suitable construction, which is connected to a fuel line 8 in turn connected to a fuel injection pump to be subsequently described.

Detachably connected to crankcase 2 by suitable screws or studs (not shown) adapted to pass through apertures 9 (shown in Fig. 2), is a nosepiece member 11. Nosepiece 11 is mounted against one wall 12 of the crankcase, which wall has an annular flange 13 in which is located one bearing structure 14 for crankshaft 16; such crankshaft 16 being also journalled in a suitable bearing structure 17 located in the opposite wall 18 of the crankcase. As is customary in radial internal combustion engines, the crank bearing 19 of crankshaft 16 carries the large end of the master connecting rod 21 connected in turn to one of pistons 22 in one of cylinders 3; auxiliary connecting rods 23 being connected to the remaining pistons 22. Crankshaft 16 extends 30 through nosepiece 11; and the projecting portion thereof is journalled in another bearing structure 24 positioned in an aperture formed in the outer wall 26 of nosepiece 11; the outer race of bearing structure 24 being retained in position 35 by means of a ring member 27 (specially shaped for a purpose to be subsequently explained) adjacent the inside face of nosepiece wall 26, and by a retaining plate 28 adjacent the outside face of nosepiece wall 26. Ring member 27 and retainer plate 28 are detachably secured to wall 26 by means of bolts 29 and nuts 31.

A portion of crankshaft 16 adjacent bearing structure 14 is splined at 32; and on such splined portion 32 is secured a driving pinion or gear 33 45 for driving gearing for a purpose to be subsequently explained. A ring 34 is positioned between the inner race of bearing structure 14 and one end of the hub of pinion 33; and another ring 36 is positioned between the opposite end of the hub of pinion 33 and the inner race of bearing structure 24. Rings 34 and 36, which are provided with suitable packing or sealed rings 35 in the periphery thereof, also serve as spacers for the described assembly on the crankshaft; and the entire assembly is held together by means

of a nut 37 screwed on the crankshaft, and which is also provided with packing or sealing rings 37' in the periphery thereof to seal the aperture in retainer plate 28.

A flywheel 41 is secured to the projecting end of crankshaft 16, and is provided with a ring gear 42 to enable engagement thereof with starting mechanism (not shown). A cooling fan 43 is also secured to the crankshaft; flywheel 41 and fan 43 being enclosed by a cover structure 44 provided with openings 46 for direction of cooling air against the cylinders of the engine. Suitable gearing 47 is connected to the crankshaft, through a suitable clutch 47', for driving of mechanism (not shown) adapted to be driven by the engine.

Peripherally mounted on the rim of nosepiece 11 adjacent wall 12 of the crankcase, are a plurality of substantially radially extending valve tappet mechanisms 51, of any suitable construction, associated with each cylinder 3 of the engine. These tappet mechanisms include the usual cam engaging rollers 52 at their inner ends and tappet rods 53 connected to the inlet valve and the exhaust valve (not shown) of each cylinder. Valve cam means 54 engaging cam rollers 52, is provided for actuating the valve tappet mechanisms. Such valve cam means 54 comprises a ring member having an outer flange 55 provided with rim portions 57 which have the usual cam lobes over which cam rollers 52 are adapted to ride. An inner flange 58 is also formed on valve cam means 54, and is journalled on annular flange 13 on crankcase wall 12; a suitable bearing 59 being positioned between flange 13 and flange 58. An annular plate 61 is detachably secured to flange 13 by means of cap screws 62 to hold valve cam means 54 in position; and integral with such plate is a bearing bracket portion 63 having sleeve portion 64 in which is journalled a hub 66 having gearing thereon for driving valve cam means 54 from the engine.

Such gearing includes a spur gear 67 splined on one end portion of hub 66, and meshing with internal gear teeth 68 on the inside of outer valve cam flange 56; the splined connection between spur gear 67 and hub 66 enabling such hub to be inserted through sleeve 64 for connection with gear 67. To retain the hub in position, a bolt 69 is provided, which has an enlarged head 71 adjacent one end thereof adapted to engage gear 67; and at its opposite end, bolt 69 has screwed thereon a nut 72 provided with a flange 73 adapted to engage the opposite end of hub 66. A driven spur gear 74 is formed integral with hub 66, and meshes with driving gear or pinion 33 on crankshaft 16. Thus, it is seen that when the engine is operating, valve cam means 54 will be driven through gears 33, 74 and 67.

Fuel injection pumps 81, one for each cylinder of the engine, are peripherally or circumferentially disposed about the rim of nosepiece 11, adjacent outer wall 26 of such nosepiece. Each of the pumps is of the type having a reciprocable plunger adapted to meter fuel by angular adjustment of the plunger about its axis, as it is reciprocated. Any suitable pump of this type may be employed in the arrangement of our invention, but we prefer to employ the type of pump which is described in detail and claimed in our assignee's co-pending application, by Lloyd E. Johnson, Serial No. 499,891, filed Aug. 25, 1943.

Briefly, each pump comprises a pump casing 82 having a pump cylinder or barrel 83 in which

5 a pump plunger 84 is mounted for axial reciprocation, and angular adjustment about its axis; the inlet of fuel being provided by a fuel inlet passage 86 formed in pump casing 82 and in communication with fuel inlet port or orifice 87 formed in the wall of barrel 83. A fuel return passage 88 in communication with inlet passage 86 adjacent orifice 87, is provided in association with a ferrule or tube 89 in inlet passage 86 for the purpose of bleeding air, as is described in the previously mentioned co-pending application. Adjacent its discharge end, pump plunger 84 is formed with the well-known annular groove 91 and slanting or scroll edge 92, adapted to work past inlet port 87 and thus control the quantity of fuel ejected as the plunger is reciprocated and angularly adjusted.

20 The tappet end of plunger 84 extends into a guide sleeve 93 slidably mounted in casing 82, and which engages pump tappet mechanism 84 removably positioned in the rim of nosepiece 11. Such tappet mechanisms 84 extend substantially radially, and each includes a sleeve 96, having an outer flange 97 supported in a recess in the rim of nosepiece 11 and containing a slidably mounted crosshead member 98 carrying a cam engaging roller 99. A tappet stem or screw 101 is adjustably mounted on crosshead 98 in free engagement with guide sleeve 93. Movement of tappet mechanism 84 in a substantially radially outward direction, by suitable cam means to be subsequently described, causes reciprocation of pump plunger 84 in one direction for fuel injection; while the return or suction stroke of the plunger is effected by means of a coil spring 102 interposed between a flange in pump casing 82 and a retainer plate 103 adjacent guide sleeve 93.

25 Gearing is provided in pump casing 82 to enable angular adjustment of pump plunger 84, comprising a gear member 104 secured to the tappet end of plunger 84, and having teeth extending through a slot in guide sleeve 93 and which mesh with another gear member 106 journalled in pump casing 82 at the side of gear member 104. Each 30 of such pump casings 82 with the described pump mechanism therein is detachably connected to nosepiece 11 by cap screws 107; and such nosepiece contains means for effecting angular adjustment of all the pump plungers simultaneously, 35 as well as means for actuating the pump tappet mechanisms.

40 The means for actuating the pump tappet mechanisms comprises annular pump cam 111 having cam lobes 112 over which the cam rollers 30 90 of the pump tappet mechanism ride. Cam 111 is journalled for rotation on an inner flange 113 formed on ring 27 which thus serves as a bearing member, and is retained in position on such flange by a detachably secured retainer plate 114. 45 It will be noted that the journal bearing at 113 for pump cam 111 is substantially radially in line with the pump tappet mechanisms 84; and the pump tappet mechanisms bear directly on the cam. This arrangement avoids deflection, and 50 thus insures true movement of pump plungers 84 with consequent accurate fuel metering.

55 To enable driving of pump cam 111 from the driving means associated with valve cam means 54, pump cam 111 is provided adjacent the 60 periphery thereof with an annular flange 116 having internal gear teeth 117 in mesh with a spur gear 118 integral with hub 66. Thus, common means driven from the engine is provided for driving valve cam means 54 and pump cam 111, 65 which includes spur gear 118 meshing with in-

ternal gear teeth 117 on the pump cam, making for an extremely compact and simple arrangement. It will be noted that the described gearing is such as to drive the valve cam and the pump cam at a reduced speed compared to engine speed because of the speed reduction provided by gears 33 and 74; pump cam 111 having the correct number of lobes to impart proper timing to the fuel injection pumps.

The means for angularly adjusting pump 10 plungers 84 to effect proper metering of fuel is governor controlled, and includes a ring gear 121 journalled on an outer flange 122 formed on bearing ring 27, and which has face teeth 123 meshing with a plurality of spur gears 124. Each of spur gears is formed at the lower end of a turntable rod 126 detachably connected to the gear member 106 in each pump casing 82. As can be noted more clearly from Figs. 2, 3 and 4, the outer end of each rod has secured thereto a collar member 127 having a recess 128 therein adapted to receive a pin 129 on an associated pump gear member 106, thus providing a detachably pin-type coupling or connection between the gearing in each pump casing 82 and each rod 126. As a result, when all the rods 126 are turned about their axis by rotation or turning of ring gear 121, all pump plungers 84 will be turned simultaneously to the same extent and in the same direction, resulting in uniform metering of fuel by all of the injection pumps.

Means is provided for detachably supporting rods 126 in nosepiece member 11 for ready assembly therein, and detachable connection of spur gears 124 with ring gear 121 when such rods are assembled. With reference to Figs. 2, 3 and 6, each rod 126 is journalled in a sleeve 131; bushings 132 being positioned between the end portions of each rod 126 and the associated sleeve. The outer end of each sleeve 131 is formed with a flange 133 adapted to seat on a shoulder 134 formed adjacent the rim of nosepiece 11; collar member 127 on each rod 126 being detachably secured to such rod over the outer bushing 132. The inner end of each sleeve 131 engages a lug or bracket 136 formed integral with the inside face of wall 26 of nosepiece member 11; and each of such brackets 136 is provided with an aperture 45 therein through which the sleeve and associated rod are insertable or removable. Thus, each sleeve and its associated rod are supported, and positioned or centered by an associated bracket 136. In this connection, the spur gear 124 on each rod 126 is small enough in diameter to pass through the aperture in the associated bracket 136.

From the preceding description, it is seen that turning of ring gear 121 effects turning of rods 126 which, through the described detachable connections with fuel injection pumps 81, cause angular adjustment of the plungers in such pumps. By virtue of the detachable connections between rods 126 and pumps 81, the pumps may be readily attached or detached from the engine without disturbing the rods; and prior to attachment of pumps 81, rods 126 and their associated sleeve assemblies may be readily attached to the engine to mesh spur gears 124 with ring gear 121. The provision of face teeth 123 on ring gear 121, adapted to mesh with spur gears 124, results in an important functional advantage because this eliminates the necessity of having to center gears 124 properly in a radial direction to adjust them for back lash so that all the fuel injection pumps may meter accurately, which would be necessary

in case a bevel gear were employed as the ring gear 121, and bevel gears were utilized in place of spur gears 124.

5 Pump tappet mechanisms 84 extend radially of the engine. However, control rods 126 and their associated sleeve 131, although they may be considered as extending substantially radially of the engine, are offset slightly from true radii. This is desired in order to enable a compact arrangement of the plunger control mechanism in the fuel injection pumps. To compensate for such offsetting of rods 126, the face teeth 123 on ring gear 121 are also offset radially by an amount corresponding to the radial offsetting of the rods. Thus, spur gears 124 will mesh accurately with teeth 123 on ring gear 121.

20 As was previously mentioned, angular adjustment of the pump plungers is governor controlled. Our preferred mechanism enabling such control is illustrated in Figs. 2, 7, 8, 9 and 10, and includes adjustable means to obtain a proper setting thereof. This mechanism comprises shafting 141 journalled in a sleeve 142 adjacent its inner end by means of suitable bearing means 142'; and having at such end a spur gear 143 meshing with face teeth 123 of ring gear 121. The outer end of sleeve 142 is formed with a flange 144 detachably connected to the rim of nosepiece 11; while the inner end of sleeve 142 is positioned and centered in the manner previously described for each sleeve 131, in a bracket or lug 146 similar to each bracket 136. Shafting 141 extends through a sleeve extension 147 detachably connected over the flange of sleeve 142, by means of cap screws 148; and to the projecting end of such shafting 141 is connected a hub 149 of a lever 151 which in turn is pivotally connected to a suitable governor linkage 152 which is connected to the engine governor (not shown).

30 For obtaining proper setting of the described mechanism, relatively adjustable plates are provided. One of these plates 153 is fixedly secured to a flange 154 on extension sleeve 147, by cap screws 156; a bearing structure 157 being provided in plate 153 to provide another journal for shafting 141 adjacent its outer end. Mounted for angular adjustment about a flange 157' on plate 153 is an adjustable plate 158 which has arcuate slots 159 therein through which extend cap screws 161 in plate 158 for securing adjustable plate 158 to plate 153, after plate 158 has been angularly adjusted to a proper position. Angular adjustment of plate 158 is effected by means of a disk 162 journalled in plate 153, and which has a pin 163 eccentrically mounted thereon and projecting through a slot 164 in adjustable plate 158. By turning disk 162, adjustable plate 158 can be turned, by virtue of engagement of pin 163 in slot 164.

60 Projecting outwardly from hub 149 is an arm 166 which is adapted to move against a stop pin 167 secured to fixed plate 153 and extending through one of the arcuate slots 159 in adjustable plate 158. Stop pin 167 determines the shut off position for the fuel injection pumps which will be always fixed. The full load stop 168 against which arm 166 is also adapted to move, is fixed to adjustable plate 158. Consequently, adjustable plate 158 provides for proper spacing between the stops 167 and 168. Plate 158 may be adjusted in the manner previously described, to enable proper positioning of the full load stop. In case a permanent setting is desired after initial adjustment, a lock pin 169 may be pressed

through suitable apertures in fixed plate 153 and adjustable plate 158, as is indicated in Fig. 9.

Passages are provided in the nosepiece of the engine, communicating with passages 86 and 88 in fuel injection pump casing 82 for circulation of fuel. An annular manifold passage 171 is provided in nosepiece 11, and is open to the outer face thereof for supplying fuel to the pumps, through radially-extending passages 172 adapted to communicate with pump passages 88; suitable sealing means 173 being provided at the junction of passages 86 and 172. An annular fuel return manifold passage 174 is also formed in nosepiece 11 and is open to the outer face of the nosepiece. Such passage 174 communicates with radially-extending passages 175 in turn communicating with the pump fuel return passages 88; sealing means 173 also provides a seal at the junctions of passages 88 and 176. Annular manifold passages 171 and 174 are conveniently closed by a sealing plate 178 detachably secured to the outer face of nosepiece 11. Fuel is supplied to the inlet manifold passage 171 from a fuel tank 170, by means of a transfer pump 181 connected by a fuel line 182 to a fuel filter 183 in turn connected by a fuel line 184 to manifold passage 171; and the return manifold passage 174 is connected by a fuel line 186 to the tank.

We claim:

1. In a radial internal combustion engine having a plurality of circumferentially disposed fuel injection pumps, each of which has a reciprocatable plunger of the type wherein metering of fuel is controlled by angular adjustment of the plunger; mechanism for angularly adjusting the plungers comprising a ring gear journaled in the engine and having face teeth, a plurality of rods each of which has at its outer end means connected to a plunger to turn it and a spur gear at its inner end in mesh with the face teeth, and means for turning the ring gear including a rod having a spur gear in mesh with the face teeth.

2. In a radial internal combustion engine having a fuel injection pump including a reciprocatable plunger of the type wherein metering of fuel is controlled by angular adjustment of the plunger, mechanism for angularly adjusting the plunger comprising a rod having at its outer end means connected to the plunger to turn it and a gear at its inner end, a sleeve in which the rod is journaled, and a bracket in the engine for positioning the sleeve and having an aperture therein through which the sleeve and the rod are insertable or removable.

3. Mechanism for angularly adjusting a fuel injection pump plunger of the type wherein metering of fuel is controlled by angular adjustment of the plunger comprising a rod having adjacent an end thereof means connected to the plunger to turn it and a gear at its opposite end, a sleeve in which the rod is journaled, and a bracket for positioning the sleeve and having an aperture therein through which the sleeve and the rod are insertable or removable.

4. A radial internal combustion engine comprising a crankcase; a nosepiece member secured to the crankcase; a plurality of circumferentially disposed fuel injection pumps detachably mounted on the nosepiece member; each of the pumps having a reciprocatable plunger of the type wherein metering of fuel is controlled by angular adjustment of the plunger; a bearing ring detachably mounted on the nosepiece; mechanism for angularly adjusting the plungers comprising a ring gear journaled on the bearing ring and having face teeth, and a plurality of rods each having a spur gear at its inner end in mesh with the face teeth; means including an annular passage in the nosepiece open to an outer face thereof for supplying fuel to the pumps; and a sealing plate detachably secured to the nosepiece for closing the passage.

LLOYD E. JOHNSON.
CARL R. MAXWELL.
